UNITED STATES PATENT OFFICE.

EDWARD C. YEAGER, OF ALLSTON, MASSACHUSETTS.

CURTAIN RING FOR FRENCH-HEADING CURTAINS.

Application filed April 28, 1923. Serial No. 635,394.

To all whom it may concern:

Be it known that I, EDWARD C. YEAGER, a citizen of the United States, residing at Allston, in the county of Suffolk and State 5 of Massachusetts, have invented certain new and useful Improvements in Curtain Rings for French-Heading Curtains; and I do hereby declare the following to be a full, clear, and exact description of the invention, such as will enable others skilled in the art to which it appertains to make and use the same.

This invention relates to curtain hangers of the type known as French-heading traverse pole rings, and has for its object to provide a curtain supporting arrangement which will enable the curtains to be readily secured to the ring and to be detached therefrom without the necessity of removing the 10 ring from the pole or the pull cords. In curtains of the French-heading type it has heretofore been customary to sew the curtain rings into the curtains, and consequently it has not been possible to take 15 down the curtain without taking down the curtain pole and removing the rings therefrom and also removing them from the curtain. This causes disarrangement of the entire lay out and necessitates the employment of skilled labor for properly re-hanging the curtains. The present invention provides an arrangement whereby curtains of the French-heading type can be easily 20 attached to the supporting rings or removed 25 therefrom in a very simple manner.

The various features of novelty and invention will appear from the detailed description taken in connection with the accompanying drawing forming part of this 30 specification, the scope of the invention being defined in the appended claims.

In the drawings—

Figure 1 is a perspective or elevational view showing curtains of the French-heading type in front of a window;

Fig. 2 is a transverse section taken on line 2—2 of Fig. 1;

Fig. 3 is an elevation of the supporting hooks which are adapted to be sewn to the 50 curtain, and

Fig. 4 is a side elevation showing the improved curtain rings on a pole with pull cords attached, the curtains being omitted.

In the drawings, 5 indicates a curtain 55 shown as made up of two pieces of fabric secured together, the top of the curtain

dividing into sections 5', thereby forming a Y-shaped head or top as is customary in curtains of the French-heading type, and 6 indicates the pole on which the curtains 60 are to be supported.

The curtain ring comprises side members 7 and 8 disposed on either side of the pole, 9 indicating a transversely extending bar from the ends of which the sides 7 and 8 65 rise, these three members constituting in effect, a U-shaped frame. Extending between the sides 7 and 8 near the upper ends thereof is a pintle or rod 10 which is adapted to support rollers 11 disposed adjacent 70 the said sides and preferably maintained in spaced relation by means of a spacer sleeve 12. By this arrangement of rollers the ring may be readily moved along its supporting pole as will be readily understood. 75

Extending from the terminals of the arms 7 and 8 are lugs 13 and 14 which are perforated to receive hooks carried by the curtain sections 5'. The curtain hooks preferably consist of the bent over terminals of a wire 15, 16 and 17 indicating said hooks. This wire intermediate the hooks 16 and 18, is bent to form a plurality of reversely 80 bent loops to provide means for attaching 85 the hooks to the curtain sections. The hook member is attached to the curtain by sewing the same thereto, the threads being looped about the bends or eyes of the loops 18. In view of the fact that a plurality 90 of loops 18 is provided, any up or down slippage or draw between the member 15 is effectually prevented. The plurality of loops 18 also provides a comparatively wide base or back to which the curtain section is 95 secured and thus turning or twisting movement of the hooks about the long axis of the wire 15 is prevented. Each curtain section 5' preferably extends beyond the upper hook 16 as shown in the drawings so as 100 to entirely conceal the mechanism between the head of the curtain and the pole.

The distance between the terminals of the hooks 16 and 17 is greater than the distance between the curtain ring lugs 13 and 14. 105 This arrangement enables the lower hook 17 to be connected or centered on the lower lug 13 before the upper hook 16 has made contact with the upper lug 14. In other words, in placing the hooks 16 and 17 on 110 the lugs 14 and 13, both hooks are not connected or hooked onto their respective lugs

at the same time, the lower hook and lug being first brought into cooperative engagement. If for any reason it should be desired to sew the curtains to the sides of the ring they may be secured thereto by passing stitches through openings 19 in the sides 7 and 8.

The curtain rings are adapted to be moved along the supporting pole by a pull cord 20. 10 Depending from the bar 9 constituting the bottom of the curtain ring, is an eye 21 to which the pull cord may be connected. As shown in Figs. 1 and 4, it is customary to attach this cord to the adjacent rings of separate curtains, the cord being looped over a pulley 22 as will be readily understood.

It will now be seen that I have provided a curtain ring which will enable a curtain of the French-heading type to be readily removed and attached thereto without the necessity of taking down the curtain pole and removing the rings therefrom or otherwise disarranging the curtain supporting mechanism.

25 While I have described the invention with considerable particularity of detail, I desire it to be distinctly understood that I intend no limitations except as may be imposed by the appended claims.

30 What I claim is:

1. A curtain support comprising a pair of side arms, lateral lugs extending from the ends of said arms and adapted to receive curtain supporting means, and means maintaining said arms in spaced relation comprising a shaft between said arms adjacent one set of said lugs, a spacing bar extending between said arms at the lower ends thereof, and rolling means mounted on said shaft.

40 2. The combination with a curtain pole and a curtain having a Y-shaped head between which the pole is adapted to be disposed, of means for maintaining the sides of the head in upright position comprising a pair of side arms, one on each side of the pole, means movably supporting said arms on the pole, and means removably securing the curtain to the said side arms comprising a pair of downwardly extending hooks attached to the sides of the curtain top, and laterally extending perforated lugs on said arms on which said hooks are removably suspended.

3. The combination with a curtain pole and a curtain having a Y-shaped head between which the pole is adapted to be disposed, of means for maintaining the sides of the head in upright position comprising a pair of side arms, one on each side of the pole, means movably supporting said arms on the pole, means removably securing the curtain to said side arms comprising perforated lugs extending from the side arms toward the sides of the curtain, and a double-hooked member secured to the curtain 65 sides, the ends of the hooks being further apart than the lugs whereby the bottom hook on a curtain side may be entered into its supporting lug prior to the other hook thereof.

4. The combination with a curtain, of a curtain hook comprising a member bent from a single piece of wire, the terminals of which are bent in the same general direction to form hooks and the intermediate portion of which is reversely bent to provide a plurality of loops, the curtain being secured to the loops, said hooks being disposed away from the face of the curtain and adapted to be hooked onto a curtain ring.

5. A curtain hook comprising a member bent from a single piece of wire, the terminals of which are straight and in alignment and bent in the same general direction to form hooks and the intermediate portion 85 of which is reversely bent to provide a plurality of loops in a common plane and which are adapted to be secured to a curtain, said terminals being disposed at one side of the plane passing through said loops.

6. A curtain support comprising an open-ended frame made from a single piece of material having a base member the ends of which are bent back toward each other, side members extending upwardly from the bent 95 over portions of the base and having their ends bent outwardly, the ends of the base member and bent portions of the side provided with openings adapted for the reception of curtain hooks, a tie member extending between the said side below the bent portions thereof, and rolling means mounted on said tie member.

In testimony whereof I affix my signature.

EDWARD C. YEAGER.
